UNITED STATES PATENT OFFICE.

CLARENCE J. LEMONT, OF SOUTH MILWAUKEE, WISCONSIN, ASSIGNOR TO LINE MATERIAL COMPANY, OF SOUTH MILWAUKEE, WISCONSIN, A CORPORATION OF WISCONSIN.

INSULATOR-SUPPORTING FIXTURE.

Application filed May 7, 1924. Serial No. 711,617.

This invention relates to certain new and useful improvements in supporting fixtures and more particularly to a secondary rack for carrying secondary wires along poles. 5 Heretofore, supporting fixtures have been made by providing a body part and insulator, bracket members made of stock material, as for example channel bars or else from special stampings, which has the objection of being a complicated structure and consequently expensive of production. Another disadvantage to that type of supporting fixture constructed of several parts riveted or otherwise secured together is that 10 special safeguards must be provided to relieve strain on the parts where joined together.

Having the above and other objections to the existing devices of supporting fixtures 20 in mind, this invention has for one of its objects to provide an insulator supporting fixture which is constructed from a single length of material to thus eliminate the necessity of riveting or otherwise joining the 25 parts together.

It is another object of this invention to provide an insulator supporting fixture of the character described in which the bracket arms and body part are formed from a single length of material, the bracket arms being formed by folding medial portions of the body part upon itself.

A further object of this invention resides in the provision of a supporting fixture of the character described having means preventing the accidental removal or detachment of the insulator carrying pin or rod.

And a still further object of this invention resides in the provision of a fixture of the 40 character described having all the advantages and none of the disadvantages of the existing types of insulator supporting fixtures and which may be readily formed from stock strip material.

With the above and other objects in view which will appear as the description proceeds, my invention resides in the novel construction, combination and arrangement of parts substantially as hereinafter described 45 and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a perspective view of an insulator supporting fixture or secondary rack embodying my invention;

Figure 2 is a view taken transversely through the fixture on the plane of the line 65 2-2 of Figure 1, and

Figure 3 is an enlarged fragmentary view, partly in section and partly in side elevation, illustrating a means for preventing accidental dislodgment of the insulator supporting or carrying rod.

Referring now more particularly to the drawing, in which like numerals designate like parts throughout the several views; the numeral 5 designates a pole or other supporting member, of any design, style or construction, to which my improved insulator supporting fixture or secondary rack is secured by bolts, lag screws or other fastening members 6.

The supporting fixture or secondary rack is formed from a single length of material 7 of a width and thickness to suit the size and style of fixture desired. Spaced, parallel bracket arms or lateral extensions 8 are 85 formed from the material 7 at medial points by being directed laterally, as at 9, and then folded back upon itself, as at 10, the longitudinal portions 11 between the bracket arms providing a body part which is attached to the pole or other supporting structure by the fastening means 6.

The bracket arms 8 are provided with longitudinal aligned apertures 12, through which extends an insulator carrying rod or 95 pin 13 having one or more insulators 14 of any desired design or shape mounted thereon. As will be readily obvious, any number of bracket arms 8 may be provided and the insulators 14 are mounted on the pin or 100 rod 13 between the bracket arms, the insulator being preferably spaced in the manner illustrated in Figure 1.

The pin or rod 13 is inserted through the apertures of the uppermost bracket arm 8 and has its upper end swaged or enlarged to provide a head 15 for limiting its downward movement. The aperture 16 in the

portion 10 of the lowermost bracket arm has its axis on an angle with respect to the axes of the apertures 12 so that when the extreme lower end portion of the supporting fixture 5 is bent to its dotted line position illustrated in Figure 3, the axis of the aperture 16 is in alignment with the axes of apertures 12, but, when moved to its full line position and secured to the support 5, the edges 17 thereof bite into the pin or rod 13 and prevent its accidental dislodgment.

From the foregoing description taken in connection with the accompanying drawings, it will be readily obvious to those skilled in the art to which an invention of this character appertains, that I provide an insulator supporting fixture or secondary rack which is of extremely simple construction, which is strongly built and which may be made in indefinite lengths and then cut to accommodate any number of insulators.

What I claim as my invention is:

1. An insulator fixture, comprising a single length of material, a plurality of bracket arms integral with and formed from said material, the portions of the material medially of the bracket arms providing an attaching body part, means adapted to be passed through the attaching body part to secure the fixture to a support, an insulator mounting pin extended through apertures in the bracket arms, an insulator mounted on the pin between adjacent bracket arms, and

means operated by the securing of the fixture to a support to prevent the accidental dislodgment of the pin.

2. In a device of the character described, an attaching body part formed from a strip of bendable material, a plurality of bracket arms projected laterally from the body part 40 and formed by folding medial portions of the body part upon themselves, whereby each bracket arm consists of two parallel, slightly spaced parts, the bracket arm parts having apertures therein and the aperture of one arm part having its axis concentric with the axis of the aperture of the other part of said arm only when said arm parts are bent to bring their inner ends in close proximity, an insulator member carrying pin insertable through said apertures, an enlargement on the upper end of the pin engageable with the uppermost bracket arm to limit the downward movement of the pin, and means 50 engageable with the body part between the bracket arms for securing the fixture to a support, said insulator pin being secured in the bracket arms against accidental dislodgment by the securing of the fixture to a support when the arm parts are moved to and held in substantially horizontal position, whereby the opposite edges of the offset aperture bind against the pin.

In testimony whereof I affix my signature.

CLARENCE J. LEMONT.
